UNITED STATES PATENT OFFICE.

VICTOR ANGERER, OF PHILADELPHIA, PENNSYLVANIA, ASSIGNOR TO THE WILLIAM WHARTON, JR., & COMPANY, INCORPORATED, OF SAME PLACE.

HOIST.

SPECIFICATION forming part of Letters Patent No. 406,251, dated July 2, 1889.

Application filed February 21, 1887. Serial No. 228,339. (No model.)

To all whom it may concern:

Be it known that I, VICTOR ANGERER, a subject of the Emperor of Austria, and a resident of Philadelphia, Pennsylvania, have invented certain Improvements in Hoists, of which the following is a specification.

The object of my invention is to construct a simple and effective brake for geared hoists, and this object I attain in the manner herein-
10 after set forth, reference being had to the accompanying drawings, in which—

Figure 1 is a transverse section of my improved hoist; and Fig. 2 is a side view looking in the direction of the arrow, Fig. 1.
15 From the hook A is suspended a frame B, made in two parts $b\ b'$, bolted together at b^2 , as shown in Fig. 1, and to the lower ends of said parts $b\ b'$ of the frame is firmly secured by pins $p\ p$ a cranked spindle C, made in one
20 piece, and having its arms $c\ d$ in the same vertical plane, as shown in Fig. 1. The arm c of the spindle forms a bearing for the drive-chain wheel D, the latter being made in one piece with a pinion a, the teeth of which engage with the teeth of an internal gear-wheel W, which is cast with or forms part of the hoisting-chain drum E, the latter having its bearing on the arm d of the crank-spindle. The crank-spindle also serves to bind the
25 lower portions of the frame B firmly together and prevent spreading of the same. The open end of the internal gear-wheel W is covered by a disk m, forming part of the chain-wheel D, and from the part b of the frame B projects a finger G, which extends over the chain-drum E and prevents the hoisting-chain from jumping. The two drive-chain guides X and Y are pivoted to the portion c of the crank-spindle C, and are held in position by a pin z.
30 On a stud projecting from the upper portion of the frame B is hung a brake-lever L, one arm l of which is attached to a rope R, within easy reach of the operator, the other arm l' being provided with a brake-shoe s,
35 which can be adjusted by means of a set-
40 screw t. This brake-shoe s bears against the rim-flange f of the chain-wheel D, and when power is applied to the arm l of the lever L the wheel D is moved laterally, so as to force the rim-flange f' against a brake-shoe T, set 50 in the portion b' of the frame of the hoist, this shoe being adjusted as required by means of a set-screw t' .
45

This hoist is what may be termed a "quick hoist," and as it is often desirable to stop the 55 chain-drum at a given point a quick-acting and powerful brake is necessary.

It will be evident that by the clamping of the rim portion of the drive-chain wheel D between the brake-shoes s and T such a brake 60 is provided.

I claim as my invention—

1. The combination, in a hoist, of the chain-drum and its operating-wheel, a frame therefor, and a brake-block carried by said frame 65 upon one side of the operating-wheel, with a brake-block upon the opposite side of the rim of said wheel carried by a lever hung to the frame, the operation of said lever causing the lateral movement of the wheel against 70 the brake-block carried by the frame, substantially as specified.

2. The combination, in a hoist, of the fixed frame made in two parts, and a crank-spindle secured to the frame and having two arms both 75 in the same vertical plane, one arm carrying the chain-drum and its gear-wheel, and the other arm carrying the drive-chain wheel and its pinion, with a brake-lever hung to said frame and carrying upon one of its arms a 80 brake-block adapted to act against the rim of the drive-chain wheel, substantially as specified.

In testimony whereof I have signed my name to this specification in the presence of two sub- 85 scribing witnesses.

VICTOR ANGERER.

Witnesses:

HENRY HOWSON,
HARRY SMITH.
